(57) CLAIM

I claim the ornamental design for a sole for footwear, as shown and described.

DESCRIPTION

FIG. 1 is a perspective view of a sole for footwear, showing my new design;

FIG. 2 is a right side view thereof, the left side view being a substantial mirror image of the right side view; and, FIG. 3 is bottom view thereof.

1 Claim, 2 Drawing SheetsFIG. 1
